UNITED STATES PATENT OFFICE.

MAX WALD, OF NEW YORK, N. Y.

PICKPOCKET-DETECTOR.

947,047.

Specification of Letters Patent. Patented Jan. 18, 1910.

Application filed October 6, 1909. Serial No. 521,232.

To all whom it may concern:

Be it known that I, MAX WALD, a citizen of the United States, and a resident of the city of New York, borough of Manhattan, in the county and State of New York, have invented a new and Improved Pickpocket-Detector, of which the following is a full, clear, and exact description.

This invention relates to an improvement 10 in garments, and particularly to a new and improved pocket, which is formed with a deep true pocket, and a shallow false pocket for the purpose of providing safety for the contents of the pocket and detecting the intrusion of a pick-pocket's hand therein.

An object of this invention is to provide 20 a device which will be simple and deceptive in construction, strong and durable, and composed of the least material consistent with a practical device.

Another object of this invention is to provide 25 a device having a deep receptacle with means for locking the opening to the same, and a shallow receptacle with means for deceiving a pickpocket.

These and further objects, together with the construction and combination of parts, will be more fully described hereinafter and particularly set forth in the claims.

Reference is to be had to the accompanying 30 drawings forming a part of this specification, in which similar characters of reference indicate corresponding parts in all the views, and in which—

Figure 1 is a side view in elevation, part 35 being broken away to show the underlying elements, showing my device as constructed in a left-hand trousers pocket. Fig. 2 is a vertical section on the line 2—2 of Fig. 1; Fig. 3 is a horizontal section on the line 40 3—3 of Fig. 1, showing the true pocket closed and locked; and Fig. 4 is a horizontal cross section on the line 3—3 of Fig. 1, showing the true pocket open and unlocked.

Referring more particularly to the separate parts of the device, 1 indicates the outer 45 fabric of the body portion of the garment. There is provided in this fabric a pocket opening 2, which may be formed therein in any suitable manner. Secured to the body of the garment in any suitable manner, as by means of stitching, in juxtaposition to the opening 2, there is provided a pocket 3, which is formed in any suitable manner, as by means of a double fold of suitable material stitched along the open edges thereof,

and which is faced by suitable facing strips 4 and 5 adjacent to the opening 2. In order to divide the pocket into a true pocket and a false or detecting blind pocket, there is provided a partition or wall 6, which is secured in any suitable manner, as by means of stitching, to the outer layer 7 of the pocket 3. This partition 6 is rather small in comparison with the pocket 3, and divides the pocket 3 into a deep true pocket 8 and a shallow blind or false pocket 9. The partition 6 is preferably formed of a strip of material doubled to form two thicknesses 10 and 11, which are secured together in any well known manner, as by means of stitching. The thickness 11 which faces the blind or false pocket 9 is provided with a plicature 12 formed out of the body of the thickness 11 and extending longitudinally of the pocket 9. The purpose of this plicature 12 is to deceive a pickpocket and make him think, when he inserts his hand in the blind or false pocket 9, that the pocket is merely turned over, thus encouraging him to proceed farther.

In order to securely lock and close the true pocket 8, there is provided a plurality of male fasteners 12^a on the inner fold of the pocket 3, and a plurality of coacting female fasteners 13 on the partition or wall 6. These coacting fasteners 12^a and 13 are of the snap-catch variety, and are readily locked together by a slight pressure.

In the operation of the device, the owner 90 places his articles in the pocket 8 and closes the opening of the same by means of the snap fastener members 12^a and 13. This leaves the true pocket 8 closed with the articles therein, and the shallow false or blind 95 pocket 9 open in alignment with the opening 2. Now, if it should occur that a pickpocket should desire to rob the owner of this device, if he operates quickly and thrusts his hand suddenly through the opening 2, his 100 hand will come in contact with the sewed-up edge of the shallow blind pocket 9, giving a sudden jerk thereto, warning the owner that he is being robbed. On the other hand, if the pickpocket should be one of the slow 105 and methodical kind, as he gradually inserts his hand, it will come in contact with the plait or plicature 12, thus receiving the impression that the pocket is merely turned over, as quite often occurs in the ordinary 110 pocket, and he will endeavor to straighten out the pocket gradually by inserting his

hand farther. This movement will cause his hand to come in contact with the side or bottom of the shallow pocket 9, again warning the owner that he is being tampered with.

5 There is thus formed a simple and efficient device, which will protect articles in a person's pocket from being stolen and at the same time form an efficient detector for warning the owner that he is being robbed.

10 While I have shown the device in connection with a side pocket of a pair of trousers, this pocket may be attached to any other part of the same or other garment.

Having thus described my invention, I
15 claim as new and desire to secure by Letters Patent:—

1. In a device of the class described, the combination with a garment, of a relatively deep true pocket and a relatively shallow 20 false pocket, said garment having an opening therein leading to said pockets, snap-

catches for locking said true pocket closed, and a longitudinal deceptive plication in said shallow pocket.

2. In a device of the class described, the 25 combination with a garment having a pocket opening therein, of a pocket secured adjacent to said opening and formed of a strip of material folded to form outer and inner layers, and a partition permanently secured to said outer layer and adapted to be removably secured to said inner layer, said partition having a longitudinal deceptive plication formed therein and extending toward 30 said outer layer.

35 In testimony whereof I have signed my name to this specification in the presence of two subscribing witnesses.

MAX WALD.
